UNITED STATES PATENT OFFICE.

CLARENCE M. STEELE, OF STATESVILLE, NORTH CAROLINA.

BRICK-CAR.

979,898.

Specification of Letters Patent. Patented Dec. 27, 1910.

Application filed April 5, 1910. Serial No. 553,476.

To all whom it may concern:

Be it known that I, CLARENCE M. STEELE, a citizen of the United States, and a resident of Statesville, in the county of Iredell and 5 State of North Carolina, have invented certain new and useful Improvements in Brick-Cars, of which the following is a specification.

This invention is an improvement in lift 10 cars for use in handling brick and has for an object among others, to provide a novel construction which can be easily operated to set the bed of the car up or down in order to lift or lower the load and which will be 15 found convenient in handling brick and other material on pallets.

The invention also has for an object to provide a lift car having only one deck making it flexible, thus allowing the wheels 20 to follow an uneven track.

The invention consists in certain novel constructions and combinations of parts as will be hereinafter described and claimed.

In the drawing Figure 1 is a longitudinal 25 section along line 1—1 of Fig. 2. Fig. 2 is an end view of a car embodying my invention, and Figs. 3 and 4 are detail views.

In carrying out my invention, I provide a main frame having side rails A bolted at its 30 ends to bearing frames B which are in the nature of hangers depending from the main frame and providing at C pivots for, what for convenience of reference, I term the rockers D, of which I employ one at each 35 end of the car. These rockers are alike except that they are rights and lefts and they are pivoted at C so they may rock in effecting an elevation and lowering of the bed A, in the use of the invention. These rockers 40 C have upwardly projecting arms C' provided with worm segments C² and the rockers also have the projecting arms C³ at an angle to the arms C' with the arms C³ of the rockers at the opposite ends of the car 45 projecting in reverse directions and these arms C³ support at C⁴ the axles of the wheels E.

To the main frame and preferably to the 50 end frames B thereof, I journal the operating shaft F which is provided with worms G made rights and lefts meshing with their respective worm segments C², as best shown in Fig. 1 of the drawing. By turning the shaft F which may be conveniently accomplished by the handle F', the worms G meshing with their segments, will tilt the rockers

on their pivots C in such manner as to raise and lower the bed of the car.

By the described mechanism, it will be noticed I simplify the construction of the 60 car, reduce the number of parts and make the car lighter, easier handled and more flexible than with the cars ordinarily in use. The operating shaft has its end thrust balanced, thus eliminating friction, so that 65 when the shaft is turned, the bearing frames in the form of rockers are swung on their pivots at C to raise and lower the car frame as desired.

It will be noticed that by the described 70 construction, I furnish a lift car having only one deck which makes it flexible and allows the wheels to follow an uneven track.

In the special construction of main frame 75 shown, I provide the two one piece frames B at each end of the car, provided with the bearings for the worm shaft and connect these frames by the two side bars which may be securely bolted in place. I also make the rockers each in one piece and pivot the same 80 to the end frames as before described. Also by the special construction of worms and segments, I am able to tilt the two rockers in unison, thus counteracting the rolling effect 85 of the wheels on the track as the load is being lifted or lowered.

I claim:

1. The combination substantially as described, of a main frame, hanger frames depending at the opposite ends of the main frame, rockers pivoted to the hanger frames and having arms provided with worm segments and also arms adapted to support axles, axles carried by said arms and provided with wheels, an operating shaft journaled in the end frames and provided with worms meshing with the segments of the rockers, the worms and segments at the opposite ends of the frame being one right and the other left, substantially as set forth. 95

2. The combination of a framing, rockers pivoted intermediate their ends thereto and having crank arms projecting from their pivots and provided with worm segments and also having crank arms projecting from their pivots at an angle to said first crank arms being provided near their free ends with bearings and wheels having their axles journaled in the bearings of said crank arms, and a shaft journaled to the framing and 105 having worms meshing with the worm segments, substantially as set forth. 110

3. The combination of a framing having end frames provided with cross bars having midway between their ends bearings for a worm shaft, the said end frames having depending hangers provided with bearings, a rocker pivoted at its ends in the bearings of the hanger and having at its ends projecting crank portions provided with bearings near their free ends, axle shafts journaled in said 10 bearings, crank arms projecting from the rockers midway between their ends and at an angle to the arms, having bearings for the axle, said intermediate crank arms being provided with worm segments and an operating 15 shaft journaled in the cross bars of the end frames and having worms meshing with the

worm segments of the rockers, substantially as set forth.

4. The combination of a frame, hangers depending from the frame adjacent the ends thereof, rockers having at their ends crank portions provided with axial bearings, axles journaled in said bearings, the rockers being provided between their ends with crank arms projecting at an angle to said first crank 25 arms and having worm segments and an operating shaft having worms meshing with said segments, substantially as set forth.

CLARENCE M. STEELE.
